UNITED STATES PATENT OFFICE.

SYLVESTER A. BAKER, OF SAN FRANCISCO, CALIFORNIA.

DESIGN FOR A RADIO LOUD SPEAKER.

Application filed July 21, 1926. Serial No. 18,445. Term of patent 3½ years.

To all whom it may concern:

Be it known that I, SYLVESTER A. BAKER, a citizen of the United States of America, residing at San Francisco, in the county of San Francisco and State of California, have invented a new, original, and ornamental Design for a Radio Loud Speaker, of which the following is a specification, reference being had to the accompanying drawing, forming a part thereof.

Fig. 1 is a front elevation of my new design, and

Fig. 2 is an edge view of the same.

I claim:

The ornamental design for a radio loud speaker, substantially as shown.

SYLVESTER A. BAKER.
